TOILET PAPER RECEPTEACLE

Original Filed Aug. 11, 1924

Patented Apr. 26, 1927.

1,626,308

UNITED STATES PATENT OFFICE.

MILO E. THATCHER, OF LOS ANGELES, CALIFORNIA.

TOILET-PAPER RECEPTACLE.

Application filed August 11, 1924, Serial No. 731,498. Renewed February 14, 1927.

This invention is a toilet paper receptacle and consists of the novel features herein shown, described and claimed.

An object is to make a receptacle or holder 5 for rolls of sheets of toilet paper, the paper being wide enough to serve as a temporary or individual cover for a toilet seat.

Another object is to build a toilet paper holder as a part of a hinged toilet seat cover 10 so that the paper will be convenient for use upon the toilet seat.

Other objects and advantages will appear from the drawings and specification.

The drawings illustrate the construction 15 and operation of the invention.

Figure 1 is a top plan view of a toilet seat construction provided with a toilet paper receptacle embodying the principles of my invention, the view being taken looking 20 in the direction indicated by the arrow 1 in Fig. 2.

Fig. 2 is a front elevation as indicated by the arrow 2 in Fig. 1.

Fig. 3 is an enlarged vertical cross section 25 on the lines 3—3 of Figs. 1 and 2 and looking in the direction indicated by the arrows.

Fig. 4 is an enlarged fragmentary vertical longitudinal sectional detail on the line 4—4 of Fig. 3.

Fig. 5 is an enlarged fragmentary side elevation on a plane parallel with Fig. 3 and as seen looking in the direction indicated by the arrow 5 in Fig. 2.

Fig. 6 is a vertical cross section on the line 35 6—6 of Fig. 4.

Fig. 7 is a diagrammatic view showing how the roll of paper is made up of overlapping sections.

The details of construction and operation 40 shown in the drawings are as follows:

The toilet seat 1 has hinge members 2 pivotally connected to hinge members 3 rigidly mounted upon the bowl 4 by hinge pins 5. Hinge members 6 are incorporated with 45 the hinge members 2 and 3 upon the pins 5. The toilet paper receptacle 7 is rigidly connected to the hinge members 6 and is a long box adapted to receive a roll 8 of toilet paper, the paper being as wide as the toilet seat 1. The receptacle 7 has flat ends 9 and 50 10 and a supporting spindle 11 is inserted through the end 9 and through a tube 12 upon which the paper 8 is wound and tapped into a hub 13 in the end 9, there 55 being a handle 14 upon the opposite end of the spindle from the hub 13 for screwing

the spindle in and out so that a new roll of paper may be inserted. The front side of the paper receptacle 7 is flat and normally vertical and open.

A door 15 is mounted upon hinges 16 connected to the bottom of the receptacle 7 and swings upwardly to close the opening. Latches 17 extend from the ends of the door 15 outside of the ends 9 and 10 to engage 65 buttons 18 upon the ends and hold the door closed. When the roll of paper 8 is exhausted the door 15 may be swung forwardly and downwardly and a new roll of paper 70 inserted.

A feed roller 19 is mounted between the ends 9 and 10 and has a spindle extending through bearings in the ends 9 and 10. A hand knob 20 is fixed upon one end of the spindle outside of the end 9. A pinion 21 is fixed upon the other end of the spindle outside of the end 10. A large gear 22 is mounted upon a stub shaft 23 in mesh with the pinion 21. A pawl wheel 24 is fixed to the gear 22. A casing 25 covers the gears 21 and 22 and the pawl wheel 24. A spring 26 pressed pawl engages the pawl wheel 24 to hold the gears from being operated backwardly. A crank 27 is fixed upon the outer end of the stub shaft 23 and when the crank 27 is operated clockwise the feed roller 19 is operated to pull the paper from the roll. A gripping roller 28 is mounted in the ends 9 and 10 to press the paper against the feed 80 roller 19.

The roll of paper 8 is mounted upon the tube 12 and while it may be a single sheet of paper, I prefer to make the roll of sections 29, the sections being overlapped as shown in Fig. 7 so that when the crank 27 is operated to feed a section 29 forwardly over the seat 1 the next section 29 will be gripped between the rollers 19 and 28 before the first section is released. The paper is fed through the opening 15^a in the door 15. 90

The paper receptacle 7 and co-operating parts are built into and form a part of the toilet seat cover 30, the front face of the cover being flat and in line with the door 15 when the door is closed so that the cover may swing forwardly and downwardly onto the toilet seat 1.

When a piece of paper 29 of the desired size has been fed from the roll and placed upon the toilet seat 1 to serve as a temporary or individual cover for the seat, the central portion of the cover may be shattered. 110

or torn in any suitable way, and after usage in the receptacle with the free end extending ³⁰ through the slot.

Various changes may be made without departing from the spirit of the invention as ⁵ claimed.

I claim:

1. In combination a toilet bowl having a seat and a cover hingedly mounted on the bowl, the cover having a receptacle formed ¹⁰ in the back face, the front face of the cover having a slot positioned adjacent the hinged mounting of the cover, and means to mount a roll of paper in the receptacle with the free end of the paper extending through the ¹⁵ slot.

2. In combination a toilet bowl, a cover hinged thereto on the upper edge, the cover having a substantially flat front face with a slot therethrough adjacent the hinge, a receptacle formed on the back of the cover and means to mount a roll of paper in the receptacle with the free end of the roll ²⁰ extending through the slot.

3. In combination a toilet bowl, a cover hinged thereto, the cover having a substantially flat front face, a door hinged to the front face, the door having a slot, a receptacle formed on the back of the cover behind ²⁵ the door, and means to mount a roll of paper

4. In combination a toilet bowl, a cover hinged thereto on the upper edge, the cover having a substantially flat front face with a slot therethrough adjacent the hinge, a receptacle formed on the back of the cover, means to mount a roll of paper in the receptacle with the free end of the roll extending through the slot, a pair of feed rolls mounted in the receptacle, one of said rolls having ³⁵ a pinion, a driving gear meshing therewith, a crank having a ratchet and a pawl on the driving gear to engage the ratchet.

5. In combination a toilet bowl, a cover hinged thereto, the cover having a substantially flat front face, a door hinged to the front face, the door having a slot, a receptacle formed on the back of the cover behind the door, means to mount a roll of paper in the receptacle with the free end extending ⁴⁰ through the slot, a pair of feed rolls mounted in the receptacle, one of said rolls having a pinion, a driving gear meshing therewith, a crank having a ratchet and a pawl on the driving gear to engage the ratchet. ⁴⁵

In testimony whereof I have signed my name to this specification.

M. E. THATCHER.
